CAVITY RESONATOR ARRANGEMENT

Leon S. Nergaard, Princeton, N. J., assignor to
Radio Corporation of America, a corporation
of Delaware

Application August 6, 1947, Serial No. 766,649

6 Claims. (Cl. 250—36)

1

This invention relates to cavity resonator arrangements suited for production of high power at ultra-high frequencies and particularly concerns oscillators, power amplifiers and the like which utilize electronic tubes and external cavity resonators.

It is an object of the invention substantially to extend the range of frequencies for which cavity resonators may be used with triodes and other tubes not of the magnetron type.

With the usual cavity resonators, it is increasingly difficult at higher and higher frequencies to obtain satisfactory performance because the resonator becomes so small that there is insufficient space therein to use coupling and tuning elements which are effective; moreover, the small dimensions of the cavity definitely limit the power which can be produced.

In accordance with the present invention, a cavity resonator employed in an oscillator, amplifier or other high-frequency circuit is of length corresponding with three or greater odd number of half wavelengths at the desired operating frequency, so to obtain sufficient space within the cavity for effective coupling and tuning elements; oscillations of frequency corresponding with the fundamental mode of the cavity are suppressed by baffles so located, as at or near voltage nodes for the desired harmonic mode, that they are equivalent to shunt elements having very low impedances at the fundamental frequency but of very much higher impedance at the desired operating frequency.

More particularly, and for use in an oscillator system, the resonant cavity structure comprises two cavities disposed side by side and provided with openings for insertion of electronic tubes having electrodes respectively connecting with corresponding walls of the cavities: the openings are so located that the tubes are at voltage anti-nodes of like instantaneous polarity for operation of the tubes in parallel relation. In one or both of the cavities, a tuning vane, or equivalent tuning element, is disposed at or near a third voltage anti-node.

Further in accordance with the invention, the cavities may be extended in direction normal to their aforesaid length to accommodate one or more additional pairs of tubes operating in parallel with the first-mentioned tubes so to obtain correspondingly increased power output from the single oscillator system.

The invention further resides in features of construction, combination and arrangement hereinafter described and claimed.

2

For more detailed understanding of the invention, reference is made to the accompanying drawings in which:

Fig. 1 is a plan view of a cavity-resonator for use with two pairs of electronic tubes;

Fig. 2 is a front sectional view taken on line 2—2 of Fig. 1;

Fig. 3 is an end sectional view taken on line 3—3 of Fig. 1; and

10 Figs. 4 and 5 are explanatory figures referred to in discussion of the invention.

Referring to Figs. 1 to 3 as exemplary of a system embodying the invention, the resonant cavity structure 10 is a rectangular metal box having parallel top and bottom walls 11—12 and an intermediate wall 13 parallel thereto and dividing the box into an upper cavity resonator 14 and a lower cavity resonator 15. The length of these cavities as measured between the end walls 16—16 is three or greater odd number of half wavelengths at the desired operating frequency. In the particular arrangement shown, the length is three half wavelengths: for operation at frequencies in the range of from about 1000 megacycles to about 1200 megacycles this dimension is about 7.5 inches.

The sides of the cavities are closed by the walls 17, 17, the width of the cavity in the particular arrangement shown in Figs. 1 to 3 being sufficiently great to accommodate two elongated electrode electron tubes disposed with their major axes in alignment and parallel to the ends 16 of the cavity structure. Each of the openings 18 in the upper wall 11 of the resonator structure 10 is in alignment with one of the holes 19 of the intermediate wall 13 and with a corresponding opening 20 in the bottom wall 12. Each series of aligned openings 18, 19 and 20 is provided to allow insertion of an electronic tube, preferably of the type disclosed and claimed in U. S. Patent No. 2,481,026 of Russell R. Law, et al. The anode of each tube is effectively connected, as by a bypass condenser (not shown) to the outer upper wall 11; the grid of each tube is connected, as by resilient contact fingers (not shown), to the intermediate wall 13; and the cathode of each tube is connected, as through a bypass condenser, to the outer bottom wall 12 of the resonator structure. The grid electrode of the tube may be defined as the control element which controls the flow of electrons from cathode to anode. The anodes of the tubes may be connected through the usual radio-frequency filter chokes to the positive terminal of a source 50 of direct current whose negative terminal is con-

nected to the cathodes either directly or through cathode resistances. A direct-current path to the grids of the tubes may be afforded by resistor, not shown, connected between the resonator casing and the negative terminal of the anode source of direct current.

Thus the upper cavity 14 defined by the upper wall 11 and the common wall 13 forms a grid-anode cavity common to all of the tubes, and the lower cavity 15 forms a grid-cathode cavity common to all of the tubes. As above stated, the length of each of the cavities between the end walls 16 may be three half wavelengths at the desired operating frequency, and in such case the openings 18 are so located that the electrodes of each tube are one-quarter wavelength from the corresponding end 16 of the cavity and are one wavelength from the electrodes of the other tube of the pair. This spatial relation is more clearly shown in Fig. 4, the electrodes of tube 21A being, as appears from curve H, at a voltage anti-node X which is one-quarter wavelength from the left-hand end wall 16 whereas the electrodes of the other tube 21B of the pair are at a voltage anti-node Y located one-quarter wavelength from the righthand end wall 16. The corresponding electrodes of the two tubes are therefore of the same instantaneous polarity. Accordingly, the phase relations are such that the tubes function in parallel and the output is therefore substantially greater than that obtainable from a cavity resonator excited from a single tube. The tubes 21C and 21D are similarly disposed and also operate in parallel relation with respect to each other and to tubes 21A, 21B.

Tuning vanes 25 and 26 are disposed at or near a voltage anti-node Z of curve H intermediate the anti-nodes X, Y at which the tubes are disposed. The dimensions of the cavity are such that the tuning vanes 25, 26 respectively associated with the cavities 14 and 15 may be of physical size affording a satisfactorily large tuning range; for example, in the particular arrangement shown the tuning range was from about 1000 megacycles to about 1200 megacycles.

Moreover, and also in contrast with the conventional cavity resonator arrangements, there is ample space for provision of effective feedback coupling between the two oscillator cavities. In the particular arrangement shown, the feedback coupling required for operation of the arrangement as an oscillator is provided by the rod 22 which threadedly engages the lower outer wall 12 of resonator 10 and extends through the opening 23 in the intermediate wall 13 of the two cavities. The desired magnitude of the feedback coupling may be effected by adjustment of the knob 24 attached to rod 22 and accessible externally of the cavity resonator 10. This feedback coupling means, because of the enhanced length of the cavities, is physically remote from the tubes.

The enhanced dimensions of the resonator also facilitate its coupling to the load. In the particular arrangement shown, power is abstracted from the cavity by a loop formed at least in part by the inner conductor 31 of a concentric transmission line 29 whose outer conductor 30 is conductively connected to the cavity resonator structure, specifically the upper wall 11 thereof. With the resonator structure shown and using four tubes of the type disclosed in the aforesaid application of Law et al., the oscillator output of about 1 megawatt, that is 1000 kilowatts, may be expected.

Generation of oscillations at the fundamental mode of the cavity, represented by curve F of Fig. 4, is effectively prevented by the short metallic baffle elements 27 which extend inwardly from the side walls 17 of the resonator structure 10 and by the intermediate baffles 27A in alignment therewith. The series of aligned baffles nearer the tube 21A are disposed at one voltage node A of the harmonic curve H of Fig. 4, whereas the series of baffles nearer the tube 21B are disposed at a second voltage node B. These baffles appear to oscillations of the fundamental mode F of the cavity as shunt impedances of very low magnitude and so effectively suppress the undesired oscillations. The width of the opening between the adjacent ends of each pair of aligned baffles of each series is so great the baffles have inappreciable effect upon oscillations of the desired harmonic frequency of operation.

For a better understanding of the effect of the baffles, an equivalent circuit arrangement having lumped reactances is shown in Fig. 5; the impedances 32 correspond with the shunt impedances afforded by the baffles 27 and 27A of Figs. 1 to 4. The condenser 33 corresponds with the feedback capacity afforded by the coupling rod 22, and the variable condensers 34 and 35 correspond with the variable capacity effect of the tuning vanes 25 and 26. The condensers 37 and 38 correspond with the anode and cathode bypass condensers, respectively. The other inductances and capacities shown in Fig. 5 correspond with the distributed inductive and capacitive effects of the resonant cavities 14 and 15. Each of the cavities is therefore equivalent to a filter network for attenuating the fundamental resonant frequency of the cavity.

It shall be understood that if a single pair of tubes such as 21A, 21B affords the power desired, the cavity resonator 10 may be correspondingly reduced in width and the intermediate baffles 27A omitted; if additional power output is required, the width of the cavity resonator may be correspondingly increased to accommodate one or more additional pairs of tubes. In the latter case, of course, additional baffles 27A should be provided to suppress oscillations at the fundamental mode.

When the cavity structure is used, as above described as the circuit components of an oscillator, baffles are preferably used in both of the cavities. When, however, it is used in a frequency-mixing or frequency-multiplying arrangement, it may be desirable to omit the baffles from one of the cavities. Other uses of the cavity resonator will be apparent to those skilled in the art.

The length of the resonator may be five, seven or greater odd number of half-wavelengths long in which event more than two tubes may be disposed lengthwise of the cavity. Whether two or more tubes are so disposed, they should each be disposed at a potential anti-node for the desired frequency of operation and they should be spaced an integral number of wavelengths. Additional baffles should be disposed at or near potential anti-nodes of the desired frequency or in any event at such locations as to serve as shunt impedances suppressing undesired oscillations of the fundamental frequency of the cavity.

When more than one pair of tubes are operated in push-push, baffles 28, Fig. 1 should be interposed between the tubes and aligned cross-wise of the tubes to ensure that these tubes function as a unity and that the magnetic field at the cor-

responding end of the cavity does not break up into loops encircling the tubes individually.

Accordingly it shall be understood the invention is not limited to the particular arrangement shown, and that changes and modifications may be made within the scope of the appended claims.

What is claimed is:

1. A resonant cavity oscillator comprising electronic tubes each having respectively an anode, a cathode and a control element, and cavity resonators having outer wall structures respectively connected to the cathodes and anodes of said electronic tubes and common inner wall structure connected to the said control elements of said tubes, whereby said resonators are coupled by operation of said tube, each said resonator having an electrical length of three or greater odd number $(2n+1)$ half wavelengths at the operating frequency and subject to oscillations at an undesired second frequency of 20

$$\frac{1}{2n+1}$$

of said operating frequency, the walls of said resonators having openings for insertion of said tubes at voltage anti-nodes of the desired frequency of operation, and metallic baffles in at least one of said resonators so dimensioned and located effectively at nodal positions for said operating frequency to appear as low shunt impedances to oscillations of said second frequency corresponding with the fundamental mode of said resonator.

2. An oscillator for generation of high-frequency oscillations comprising a cavity resonator of electrical length in one direction approximately corresponding with three or greater odd number of half wavelengths at the desired operating frequency, at least one pair of metallic baffles spaced at half wavelength intervals along said direction at nodal points at said operating frequency within said cavity structure to suppress oscillations at the fundamental mode thereof, oscillator tubes inserted in said cavity structure at voltage anti-nodes at said operating frequency of like instantaneous polarity for in-phase operation and on opposite sides of said point of baffles thereby to couple said cavities by operation of said tubes, and tuning vane structure extending into said cavity structure at a voltage anti-node of instantaneous polarity opposite to that of said first-named anti-nodes and between said pair of baffles.

3. An oscillator comprising two cavity resonators disposed side by side with a common wall portion and having a length corresponding with three or greater odd number of half wavelengths at the desired operating frequency, two pairs of electron tubes disposed within said resonators and coupling said resonators and having like elongated anode, cathode, and grid electrodes oriented transversely to said cavity length and each connected to the corresponding wall structures of said resonators with said grid electrodes being connected to said common wall portion, each of said pairs of tubes being disposed at a voltage anti-node of the same instantaneous polarity as the voltage anti-node at which the other pair is disposed and in alignment with a corresponding one of the other pair of tubes.

4. An oscillator comprising two cavity resona-

tors disposed side by side with a common wall portion and having a length approximately three or greater odd number of half wavelengths at the desired operating frequency, two pairs of elongated electrode electron tubes to couple said resonators and having like electrodes including grid electrodes connected to corresponding wall structures of said resonators with said grid electrodes connected to said common wall portion and all said tubes disposed with their major axes normal to said length, the tubes of one pair being disposed at a voltage anti-node having the same instantaneous polarity at which the tubes of the other pair are disposed, and baffles within at least one of said cavity resonators between said pairs of tubes at voltage nodes of oscillations of said desired frequency and appearing as low shunt impedances to any oscillations of the fundamental frequency of said cavity resonators.

5. An oscillator comprising cavity resonators disposed side by side and each with a common wall portion having a dimension along one length corresponding with three or greater odd number of half wavelengths at a desired operating frequency, baffles located in each of said cavity resonators at voltage adjacent nodes of the desired frequency, aligned transversely elongated openings in said cavity resonators at voltage anti-nodes of the desired operating frequency, and electronic tubes to couple said cavity resonators positioned on opposite sides of said baffles in said openings with their like electrodes including grid electrodes connected to the corresponding wall structures of said cavity resonators, said grid electrodes being connected to said common wall portion.

6. A cavity resonator structure to be excited by two pairs of electron tubes and comprising two cavity resonators disposed side by side with a common wall portion and having a length corresponding with three or greater odd number of half wavelengths at the desired operating frequency, two pairs of aligned transversely elongated openings in the wall structure of said resonators for insertion of two pairs electron tubes with elongated electrodes including grid electrodes, each of said pairs of openings being disposed at a voltage anti-node of the same instantaneous polarity as the voltage anti-node at which the other pair is disposed, said grid electrodes being connected to said common wall portion.
